UNITED STATES PATENT OFFICE.

NATHANIEL BANKS CREGIER, OF CHICAGO, ILLINOIS.

SIGNAL SYSTEM.

1,274,514.

Specification of Letters Patent.

Patented Aug. 6, 1918.

Application filed January 5, 1911, Serial No. 600,989. Renewed January 4, 1918. Serial No. 210,377.

To all whom it may concern:

Be it known that I, NATHANIEL B. CREGIER, a citizen of the United States, residing at Chicago, county of Cook, and State 5 of Illinois, have invented new and useful Improvements in Signal Systems, of which the following is a specification.

This invention relates to improvements in combined signal and telephone systems, 10 and particularly to systems that are adapted for use for fire alarm telegraph purposes and it is an object of the invention, among other things, to arrange the system so that a pair of metallic conductors may be used 15 for each box or sub-station, the system being thus operable when desired by a completed metallic circuit.

It is also an object of the invention to provide means for using ground connections, 20 in addition to a single pair of metallic conductors, affording a system in which two distinct circuits or paths from each box or sub-station to the central station or office is provided and so arranged that impulses or signals may be received over both 25 paths or circuits simultaneously or alternately or over either one or the other separately as may be desired.

It is also the purpose to provide a system 30 in which grounded or metallic circuits are used, with means for taking records of the impulses or signals transmitted, whether the system be operated through its grounded connections or through its complete metallic circuit connections.

It is a further object of the invention to provide a system having relays or signal devices so arranged within a circuit that one or more relays or signal devices will 40 be common to all the lines and will operate with impulses through the ground only, while other relays or signal devices will operate only when the line is metallically closed.

It is also an object of the invention to 45 provide a system of the type mentioned, in which recorders are provided which are common to all the lines, but which are capable of being cut off with respect to any 50 individual line or lines, and duplicate or extra recorders substituted.

The invention further has for its object the provision of a system by which a preliminary, manually closed and independent 55 alarm from each box or sub-station may be given in advance of the alarm signals sent

in by the character wheel or mechanism at such box or substation, which preliminary alarm will cause the operation audibly and visually of signals associated with each circuit, the preliminary warning thus obtained being especially valuable in the event of a failure of the box-mechanism to operate properly.

A still further object of the invention is 65 the provision of a system of the type mentioned, in which a series of circuits are perpetually electrically closed, affording opportunity for making an absolute test of the system or any of its lines at any time.

The system forming the subject matter of the present invention is provided with an auxiliary circuit which can be connected with the main lines when there is trouble at any point thereon, the arrangement of the 75 circuit thus connected up being such that a record of signals or impulses will be made whether the line connections are short circuited, grounded or the line is open at any point on either conductor. In this manner 80 records are made even though there is trouble upon the line at any point.

It is a further object of the invention to provide a fire alarm signal system in which an all metallic circuit is provided and extended to each engine house of the system, 85 the said all metallic circuit being also provided with grounded connections the system embracing further a signal arranged at the central station and capable of operation by 90 a circuit completed through the grounded connections of the system.

It is also an object of the invention to provide conductors extending from the central station to the engine house of the system 95 and arranged with ground connections therefor, adapted to be completed by the wheels or movement of any vehicles which leave the engine house, whereby a signal is operated in the central station indicating that the 100 fire company has responded to the call, the mechanism being so arranged also that a signal can be further sent to the central station when the fire apparatus has been returned to the engine house.

It is a still further object of the invention to provide such a system with metallic connections extending to individual engine houses which can be used not only for indicating when the engine leaves the house 110 and is returned, but which is also capable of use as a telephone line for the purpose

of telephoning from the engine house to the central station and vice-versa.

With these and other objects in view the invention comprises the constructions, combinations and arrangements of parts hereinafter described and claimed.

In the drawing forming a part of the specification—

Figure 1 is a diagrammatic view illustrating the circuits employed in this system, together with the apparatus actuated thereby.

Fig. 2 is a diagrammatic view of an auxiliary circuit employed for insuring the obtaining of a record of impulses or signals.

Fig. 3 is a diagrammatic view of an individual circuit which is capable of being connected with the main line whenever it is desired to individualize incoming signals or impulses over the main line.

Fig. 4 is a fragmentary diagrammatic view of a map indicator showing the manner of displaying indicating light signals in connection with a diagram of streets.

Fig. 5 is a diagrammatical view showing connections employed at each engine house by which a signal is transmitted to the central station over the line wires showing that the engine has departed and also illustrating means for using a telephone at the engine house and obtaining connection with the central station for talking therewith.

Fig. 6 is a diagrammatic view showing a detail of a telegraph set that may be used in the central station in telegraphing to a box or sub-station and actuating a polarized bell therein.

Fig. 7 is a diagram illustrating the modification using a normally closed circuit, also showing a plurality of signal box circuits connected to the devices in the central station common to a number of individual lines.

In carrying out the features of the invention a central station is employed having connection with the main line wires which extend from said station to all parts of the system. There is also employed an inside circuit which is employed for operating all of the mechanism used within or about the station. The various circuits and connections and the apparatus operated thereby have been indicated upon the diagram in the drawing and the invention will now be described, reference being had thereto.

The line conductors are indicated in the diagram at 1 and 2 and are connected with a battery as at 3. The said line conductor 2 extends to all of the call boxes of the fire alarm system, one of such call boxes or stations being indicated within the dotted line 60 at 4.

The circuit provided for the inside or station apparatus is provided with the main conductors 5 and 6 which are connected with an actuating battery or batteries 7. The actuating battery 3 of the line wires is so

connected that impulses may be sent through the ground connection at 8 from any one of the stations 4, there being a ground connection 9 with such station. The usual alarm producing mechanism at the station 4 is also capable of completing a metallic circuit through the battery 3 over the line wires 1 and 2 which operate the signals, sounding devices, lamps and recording instruments located at the central station.

One of the line conductors as 1 also includes the winding 10 of a differential relay mechanism 11 at the central station and also a winding 12 at a relay 13 at said station. The conductor 2 of the main line also includes winding 14 of the relay 11 arranged parallel with the winding 10 when a current is passed at the same time through the winding 14. At such a time a relay 11 would not be affected while the relay 13 would impart impulses to the lamps, recording instruments and sounding devices employed at the central station, and also closing a circuit through a relay for setting a recording device, which will be hereinafter fully described.

The relay 13 is so connected, that only the metallic closing of the line wires will actuate the same and cause it to send impulses to the lamps 15 and 16 and the relay 17 of the sounding device or tap-bell 18. At such time the current from the battery 3 passes over both of the line wires 1 and 2 and the windings 10 and 14 of the relay 11 are neutralized and the said relay is not operated. A current is also sent to relay 23 through the jack 77 for setting a recording mechanism in operation as hereinafter described.

In operating the usual character wheel or dial 19 at an alarm station or box, the contacts 20 and 21 are brought together producing a metallic short through the line wires 1 and 2 for the number of signals to be indicated at the central station by the lamps 15 and 16 and sounding device or tap-bell 18.

Associated with the circuit which causes the actuation of the said lamps and sounding device, is a recording instrument 22 which is set into operation by the actuation 11 of the relay 23. The relay 23 is so connected with the lamp circuits 15 and 16 that it is actuated when the flashes or signals are sent to said lamps. The recorder 22 is usually of the ordinary pen operating type 12 adapted to make marks or designations upon a strip or roll. The recorder 22 is common to all of the lines of the sub-station but may be cut off from any individual line and left for actuation by the others by the use of an individual circuit and plug therefor as will be hereinafter more fully described.

The first circuit employed, however, in turning in an alarm at a box or station 4 is a ground circuit which is closed by contacts 13

24 and 25 which are manually temporarily brought together in pulling down the usual hook or lever that is commonly employed at such alarm boxes for setting the mechanism 5 therein in operation. Upon closing the circuit at the contacts 24 and 25 a circuit through the battery 3 and the ground 8 including the windings of a relay 26 is completed. The current of the battery then 10 passes over the line wire 2, winding 14 of relay 11, and the branch connection therewith at 27. The contact 24 is also connected by a branch conductor 28 through which the current reaches the ground at 9. The 15 ground circuit thus automatically completed operates the relays 11 and 26, adjustable group relay 26 closes a circuit through the recorder 29 which gives a preliminary mark upon the recording strip indicating that an alarm 20 is to follow closely. The circuit completed by the relay 26 is connected with the bus bars 5 and 6 so as to include the battery 7 by conductors 30 and 31, armature 32 and conductor 33.

25 Conductor 33 extends to a key mechanism 34 of ordinary type which when set in one direction engages the contacts 35 directing the current through the winding of the recorder 29. When the key is set in the opposite direction it directs the current through the contacts 36 to the winding of a sounding mechanism 37 as clearly indicated in the diagram of Fig. 1.

30 The group recorder 29 is common to all of the signal station box connections that come into the central station and under ordinary conditions insures the obtaining of an indelible record or the operating of a sounder whenever a call comes in. As heretofore stated the contacts 24 and 25 only produce a temporary grounding of the circuit through the battery 3 and a preliminary operation of the recording mechanism 29 or the sounder 37 as the case may be, and also the lighting of lamps as will be hereinafter fully described which gives a preliminary visual permanent signal of an incoming call and indicates the box or station from which the call has been sent.

35 As the character wheel of the signal box 4 begins to send impulses by means of the contacts 20 and 21, the said contacts are also forced far enough to one side to engage a third contact 38 which again completes a circuit from the ground 9 and conductor 28 to the line wire 2 and through the battery 3, relay 26 and ground 8 so that the recording device 29 is again operated. This ground connection will be completed as often as the impulses are sent by the character wheel at the box and will thus produce and record in exact correspondence with the flashes at the lamps 15 and 16 and with the sound of the tap-bell 18. The 40 lamps 15 and 16 are preferably of one color

as for instance white to distinguish from signals over other lamps used in the system which will be hereinafter described.

45 The ground circuit described through the ground 8 and 9 and the battery 3 together with the line wire 2 carries a current through one of the windings of the relay 11, namely a winding 14 so that the said relay is operated by the ground circuit operating the drop armature indicated at 39. In this way 75 a circuit is completed through lamps 40 and 41 and through relay 42 over conductors 43 and 44 with the local bus bars 5 and 6 and the battery 7. As the armature 39 remains in the position to which it is brought by the 80 first closing of the ground circuit until it is reset as will be hereinafter described, the lamps 40 and 41 will remain lighted. The relay 42 actuates an armature 45 which completes a circuit through a lamp 46, the lamp 85 circuit being connected by a conductor 47, to local bus bars 6 on one side of the circuit, and by conductor 48 with the local bus bar 5 upon the other side of the circuit, and the 90 battery 7.

95 The lamp 46 is thus also lighted and is so located as to be a warning to the operator at the central station that a call is to come into the station over one of the lines. The lamp 40 is one of a number of lamps which is placed upon a convenient map as 49, shown in Fig. 4 located in the central station. One of said lamps 40 is placed on the map at the point where the local sub-station is positioned in the locality or section. The 100 positions of such lamps upon the map are indicated at 50 and 51. Of course as many lamps are employed as there are call boxes throughout the section covered by the fire alarm system. The lamp 41 designates one of a number of lamps which are conveniently located in the central station opposite a designating index, giving the number of the alarm boxes and also the street or streets where the same 105 are located.

110 Associated with the circuit of the lamp 46 is a circuit for a sound mechanism which is normally adapted to be closed by relay 52 which is actuated when the lamp 46 is lighted. The armature of the relay 52 completes a circuit through wires 53 and 54 which are connected with the main conductors 5 and 6 and the battery 7. Included in the line 54 is a gong mechanism 55 which is set in 115 operation by the completion of the circuit through the armature of the relay 52. A key or switch 56 is located in the branch conductor 54, which can be operated to cut out the gong mechanism, as it is usually undesirable to allow it to continue ringing. The 120 lights 40 and 41 and 46 remain lighted until the armature 39 is restored and this is accomplished by a manually operated key, which closes a circuit through the third 125 winding 57 of the relay 11 with the local 130

bus bar 5 and 6 and the battery 7 of the central station. The actuation of the winding 57 may also be accomplished for the same purpose of restoring the armature 39 by placing a plug in jack 58 as will be herein-after more fully described.

In order that every call box or sub-station line may be always open to a direct current over the main line wires 1 and 2, the 10 said boxes are each provided with a polarized bell as 59, which is connected with the line wires 1 and 2 by branch wires 60 and 61. A condenser 62 however, is interposed in the conductor 61, for preventing a passage of a 15 direct current at the bell. The bell will, however, always respond to an alternating current sent over the line wires 1 and 2 from the central station, and can be thus used to call a party to the box for telephoning, providing of course the said party is in the immediate vicinity of said box. A switch or key 63 is provided in the box also for shunting the condenser for telegraph or code 20 signaling purposes. A jack 64 is also connected with the branch wires 60 and 61 so that an ordinary telephone hand set may be 25 plugged in at the same jack and a connection can thus be obtained with the central office or station for communicating therewith by 30 telephone.

In the central office the telephone connection is obtained through conductors or wires 35 65 and contact springs 66 and 67 together with conductors 68. The conductors 68 are connected with contacts 69 which may be 40 connected at any time with the conductors 1 and 2 by the moving of contacts 69. A circuit is thus capable of completion from the telephone in the central station with the telephone which may be plugged in at any one 45 of the fire alarm boxes. In order to be able to test the different boxes also, the telephone set at the central station may be cut out by spreading the contacts 67 so as to disconnect 50 them from the contacts 66 and bring them into engagement with the contacts 71 of a pair of conductors 72 which form leads from a testing generator as indicated in Fig. 1, the connection from the testing generator being 55 thus possible from the central station with any of the local call-boxes or sub-stations. Any desired or well known method of testing may be employed.

The movement of the circuit changing contacts 67 is usually effected by means of a 60 manually operated key which is preferably automatically restored to its normal position. The contacts 70 are also operated by a manually operated key which, however, is generally manually restored.

The operation of the third winding 57 of the relay 11 for resetting the armature 39 as heretofore referred to, is usually accomplished by a manually operated key arranged 65 to move the contact 73 against the contact 74.

The contact 73 is connected with the main wire 5 while the contact 74 is connected by a conductor 75 with the said winding 57. The winding 57 reaches the other local bus bar 6 through the conductor 44 as heretofore described. The jack sleeve 58 is interposed in the conductor leading to the winding 57 as shown in Fig. 1.

At the jack sleeve 58 a pair of contacts 76 are employed which are adapted to break 75 the connections with the line wires 1 and 2 at the central station so that a plug inserted in the jack sleeve 58 and arranged to spread the contacts 76 will cut out all of the office connections back of said jack at the same 80 time furnishing battery to sleeve 58 to restore armature 39.

As there are a great many lines from different boxes coming into the central or office station, and the recorder 22 is common to all 85 of the lines it is desirable to place the individual call upon an individual recording means so that the recorder 22 may be left ready to receive another call that may come in at or about the same time. For this reason a jack 77 is provided in the conductor which is connected with the relay 23. In Fig. 3 a local recording and sounding mechanism is indicated in diagrammatical form, the plug 78 of which may be inserted in the 90 jack 77 so as to disconnect the individual box line which has sent in the call from the recording mechanism 22. The plug 78 is provided with a conductor 79 which includes a pen register 80 and beyond which register 100 it may be connected with the proper line wire of the batteries 7. The conductor 79 also includes a key or switch mechanism 81 which may be operated to cut out the pen recorder 80 and send the impulses over a conductor 82 which includes a sounder 83 of ordinary construction. By the operation of the key 81 either the pen recorder 80 or the sounder 83 may be caused to receive the incoming impulse or message from the individual box.

In the event of trouble of any kind occurring upon the outside lines 1 and 2, it is important to provide a means whereby the alarms or messages sent in may still be received and recorded until opportunity is given for correcting the trouble and restoring all of the mechanism to its normal condition. For this purpose a trouble auxiliary recording circuit commonly designated as 11 the hospital circuit, is provided and embraces a two way plug 84 which can be inserted in the jack 58 thereby cutting out as heretofore described all of the inside or central office connections, from the line which 12 is disabled.

Inasmuch as the battery 3 is thus cut off, a battery 85 is used in connection with the plug 84, the said plug being connected therewith upon one side by a conductor 86, 13

Upon the other side the plug is provided with a conductor 87 which normally reaches the other side of the battery through contact 88, contact 89, conductor 90, relay 91 and conductor 92, forming component parts of a different key mechanism. The connection between the conductor 87 and the conductor 90 is so arranged, however, that the relay 91 can be made to respond to either impulses through ground or by the metallic closing of the line. When the contacts 88 and 89 are in engagement with each other, the hospital circuit is prepared to take care of grounded lines when the line is metallically completed.

If the line is short circuited or open the contacts 89 are spread so as to be disconnected from the contacts 88 and brought into engagement with contacts 93, so that the circuit through the ground, indicated at 94, is obtained and through either one of the conductors 86 and 87 of the plug. The completion of a circuit from the battery 85 through the relay 91 operates to close, by means of the armature 95, a circuit through the pen recorder mechanism 96. The recorder 96 is connected with the local bus bars 5 and 6 of Fig. 1. This gives opportunity to have the trouble cured and at the same time preserves a record at the office of all the incoming calls which can be acted upon in the usual way.

From the above description it will be evident that the system forming the subject matter of the present invention is adapted for use both in connection with metallic circuits or ground impulses in receiving alarm calls from outlying stations or boxes. The number of call boxes of course may be multiplied to any desired extent for the requirements of the locality and the recording instruments 22 and 29 are common to all of the lines. Each individual line is provided with lamps 40 and 41 and with code signal or flash lamps 15 and 16. The pilot lamp 46 is common to all of the lines as is also the gong mechanism 55. Immediately upon receiving conflicting code signals as indicated by more than one lamp on map 50 an individual circuit such as illustrated in Fig. 3 is switched into each circuit relieving the common recorder 22 and substituting an individual recorder 80 for each individual signal. The hospital circuit is always in readiness in the event of trouble occurring upon the line at any point. Telephone communication can also be obtained from any call box to the central station, and vice-versa if someone is at or near the signal box.

As heretofore indicated the polarized bell 59 and the key 63 located in the local signal box or sub-station may be employed for telegraph purposes in connection with the central station. When telegraphic communication is thus to be used a telegraph set at

the central station as illustrated in Fig. 6 in diagrammatical form, is plugged into the line at jack 58 connected with the signal box to be communicated with. The said telegraph set is provided with a plug 97 one side of which, as for instance the sleeve, is connected by a conductor 98 with the wire 1 of battery 3, and the other side of the said plug, as for instance, the tip is connected with a conductor 99 which passes to a relay 100 and from this a conductor 101 leads to a telegraph key 102. The said key 102 is connected with the wire 2 of battery 3, it being the same as wire 2 indicated in Fig. 1.

By the operation of the key 102 the impulses may be sent to the signal box or sub-station, each movement of the key producing a sound of the polarized bell 59 at the signal box and making it possible to send the usual code messages. The completing of the circuit through the relay 100 also operates an armature 103 which completes a circuit through the conductors 5 and 6 at the station, the said conductors being the same as indicated in the diagram of Fig. 1, the circuit completed by said armature 103 passing through the winding of a telegraph sounder as 104.

In this manner the sounder 104 is in position to receive impulses from the signal box whenever the key 63 therein is operated. Thus code signals can be returned from the box to the central station.

The present system is also arranged for indicating at the central station the fact that the engine has left the engine house and at a later period, to show when it has been returned thereto. A portion of the same connections are also employed for obtaining telephonic communication with the engine house. The means for accomplishing this purpose is clearly indicated in the diagram of Fig. 5 in which a contact making device, as for instance a plunger 105, is located in the floor of the engine house immediately in front of one of the wheels of the engine or other fire apparatus. A spring contact 106 which normally elevates the pin is adapted to be depressed thereby as the engine or other vehicle leaves the house, completing a circuit through a ground connection at 107 and through contact 108, conductor 109, the winding of a relay 110, conductor 111, the contacts 112 of the jack 113, conductor 114, the windings 115 of a relay 116 and thus to conductor 5, being the same as shown in the diagram of Fig. 1, through battery 7 and to the ground indicated at 177 of Fig. 1.

The circuit thus completed operates an armature 118 at the relay 116, making a connection between conductor 119 of the lamp 120 and bus bar 6 which is connected with the battery 7 as in Fig. 1, the current passing thus to bus bar 5 and back to the map or index lamp 120 by means of conductor 141. 130

The passing of the current through the lock up relay 110 causes it to operate armature 134 thus completing a ground connection at 136 through a back contact release key 135.

- 5 The ground connection is thus preserved through the lamp 120 for keeping the same lighted until the engine has been returned to the station and put in place again back of the plunger 106. At that time the person 10 in charge of the engine house, operates the back contact 135 for breaking the circuit through ground 136 and thus causes the extinguishing of the light 120, so that those at the central station know that the engine has 15 returned to the engine house.

The fire alarm station in each instance is also provided with a telephone mechanism as at 129 which is adapted to be connected with conductor 130 by conductor 137, the 20 conductor 130 being connected with the conductor 111. The telephone mechanism is also connected with the jack mechanism 113 by means of the conductor 128 and branch conductor 138, a condenser 140 being interposed in the conductor 128. A polarized bell 139 is connected between the conductors 137 and 138. Through the conductors 128 and 130, and 111 the telephone mechanism is capable of connection at the jack 113, through 25 its contacts with the conductors leading to the bus bars 5 and 6 and the battery 7.

In completing the circuit through the telephone mechanism by taking down the receiver in the usual way, a current is passed 30 over bus bars 5 and 6 and through the battery 7 over both the windings 115 and 124 of the relay 116 so that the said windings do not affect the armature 118, the action of one winding neutralizing that of the other. The 35 current from conductor 6 however passes over bus bars 5 and 6 and through the battery 7 over both the windings 115 and 124 of the relay 116 so that the said windings do not affect the armature 118, the action of one winding neutralizing that of the other. The 40 current from conductor 6 however passes through the winding 125 of the relay 123, and thence to the jack 113 over conductor 126 and contact 127, and from thence to the telephone mechanism. The passing of the 45 current over the winding 125 operates the relay 123 for closing the armature 122. A circuit is thus closed through lamp 132 making a signal in the central station indicating that parties at the fire engine house desire 50 to communicate with the central station by telephone. The current through the lamp 132 passes over the conductor 133, conductor 141, bus bar 5, batteries 7, bus bar 6, conductor 121, armature 122, and conductor 131 to 55 the lamp 132. The lamp 132 is located in close proximity to the particular jack 113 that is connected with the engine house sending the call and the plug of a telephone mechanism at the central station is then 60 inserted in the jack 113 so as to obtain communication with the engine house.

When it is desired to call up the engine house from the central station a plug is inserted in the said jack 113 and a ringing current sent over the conductors 128 and 130

through the condenser 140 and the polarized bell 139, operating the same. Upon using the telephone the condenser 140 and the bell 139 are cut out, the connections with the jack 113 being thus established as heretofore described. 70

It will be evident that the system above described and operable in connection with the various signal boxes can be operated in a reverse condition, namely with a closed 75 circuit to each box or alarm station, so that when the box mechanism or character wheel 19 operates, it will open the pair of conductors for each impulse or signal and close the ground contact with the wet or battery 80 side of the circuit.

This is clearly illustrated in Fig. 7 in which all of the common and battery bus bar leads are shown to the left of dotted line α — α , the signal box being numbered as before, the line wires 1 and 2 forming a closed metallic circuit, being the same but shown connected to their battery bus bars 151 and 152 respectively. Relay 13 is permanently in circuit and its armature pulled up, and 90 operates with each impulse of the code signal wheel to a back contact—the reverse of its operation as shown in Fig. 1. No condenser is necessary, and the spring contact 20 is connected to the battery or wet side 95 of the circuit. The rest of the circuits and devices operating as in the normally open circuit, the different leads to other individual signal pairs being partly outlined at 160, the ground to the plus side of the battery 7 being numbered 177. 100

Bus bar 153 is common to the lighting circuit of flash code lamps 15 and 16 and battery 7 including common recorder relay 23.

Bus bar 154 is common to flash lamps and 105 tap bell signal 18.

Bus bar 155 is common to the light circuits of red map lamps 40 and index lamps 41 of each circuit together with common pilot lamp 46. 110

Bus bars 156 and 159 are common ringing leads, and bars 157 and 158 are common to telephone leads. In this figure, the contact 25 is shown connected direct to the operating lever 161 with its hook, for diagrammatic purposes, though the contacts are separate and insulated from the hook in practical use. 115

What I claim is:—

1. A signal system comprising line wires extending from a central station to stations, the said line wires being adapted to send impulses through ground connections and through all metallic connections, a source of electrical energy connected with said line wires, a ground connection with said line wires, a ground connection with one side of the source of electrical energy, a ground connection capable of being completed at the signal stations, and a relay operable by completing the ground connection at the signal stations 120
2. A signal system comprising line wires extending from a central station to stations, the said line wires being adapted to send impulses through ground connections and through all metallic connections, a source of electrical energy connected with said line wires, a ground connection with one side of the source of electrical energy, a ground connection capable of being completed at the signal stations, and a relay operable by completing the ground connection at the signal stations 125
3. A signal system comprising line wires extending from a central station to stations, the said line wires being adapted to send impulses through ground connections and through all metallic connections, a source of electrical energy connected with said line wires, a ground connection with one side of the source of electrical energy, a ground connection capable of being completed at the signal stations, and a relay operable by completing the ground connection at the signal stations 130

for operating a permanent visual signal in the central station.

2. A fire alarm signal system comprising line wires extending from the central station 5 to individual engine houses, lamps arranged at the central station upon an indicating map of the locality, a relay mechanism at the central station capable of having a ground connection for completing a circuit 10 through said lamp, a source of electrical energy at the central station grounded connections at the individual engine house operable by the wheels of the engine for actuating said relay and lighting the lamp, and 15 mechanism at the engine house for preserving the ground connections until purposely broken, for maintaining the lamp at the central station in its lighted condition until the engine has been returned to the house.
- 20 3. A signal system, comprising a battery, a plurality of line wires extending on opposite sides of said battery terminating in various signal stations, normally open switch members on each of the line wires 25 in said signal stations, a ground connection leading from one of the line wires adjacent the switch member in each station normally out of connection with the line wire, a single permanent ground connection on one side 30 of the battery, a relay on said last named ground connection, a normally open local circuit controlled by said relay, and means for operating the switch members of the line wires at each station and simultaneously 35 close the circuit to the ground, whereby a circuit will be completed through any one or more of the line wires and at the same time through the signal relay on the ground circuit to operate the latter and close the 40 local circuit.
4. In a signal system, a plurality of pairs of line circuits a single source of electrical energy for said circuits, a single permanent ground connection leading from one side 45 of the source of electrical energy, a relay on said ground connection, a normally open local circuit controlled by said relay, a normally open ground connection on each line circuit on the opposite side of the source of 50 electrical energy adapted to be automatically connected with the line circuit on closing of the latter to complete the ground circuit through the relay simultaneous with a circuit through the line circuit, means for 55 closing the line circuit independent of the ground circuit, a relay on each line circuit, and a local signal circuit controlled by said relay, said relay adapted to operate only on the closing of the ground circuit.
- 60 5. In a signal system comprising a source of electrical energy, a plurality of metallic conductors connected thereto extending from opposite poles of said source of electrical energy to substations to form pairs, 65 one pair to each substation; an individual

differentially wound relay interposed in each pair of metallic conductors; a permanent signal circuit controlled by said relay, electrical contact making means in circuit with said pairs, one at each substation; a ground circuit at each substation including a ground contact normally out of electrical connection with said conductors; a permanent ground connected to one pole of said source of electrical energy; an electrically operated signal device interposed in circuit with said permanent ground; means at each substation for operating the electrical contact making means and the ground contact whereby a metallic circuit will be completed through either or both of the metallic conductors and at the same time completing a circuit through the signal device interposed in circuit with said permanent ground. 70 75 80

6. In a signal system comprising a source of electrical energy; a plurality of metallic conductors connected thereto extending from opposite poles of said source of electrical energy to substations to form pairs, one pair to each substation; an individual electrically operated signal device having a member interposed in one member of a pair and a second member, interposed in the other member of said pair; a permanent signal controlled by said system; electrical contact making means in circuit with said pairs, one at each substation; a ground circuit at each substation including a ground contact normally out of connection with said conductors; a permanent ground connected to one pole of said source of electrical energy; an electrically operated signal device interposed in said circuit with said permanent ground; means at each substation for operating the electrical contact making means and the ground contact whereby a metallic circuit will be completed through any one or more of the metallic conductors and at the same time completing a circuit through the signal device interposed in circuit with said permanent ground. 85 90 95 100 105 110

7. In a signal system comprising a source of electrical energy; a plurality of metallic conductors connected thereto extending from opposite poles of said source of electrical energy to substations to form pairs, one pair for each substation; an individual differentially wound relay interposed in each pair of metallic conductors; a permanent signal controlled by said relay; an individual electrically operated signal device interposed in one member of each pair of metallic conductors; electrical contact making means in circuit with said pairs one at each substation; a ground circuit at each substation including a ground contact normally out of electrical connection with said conductors; a permanent ground connected to one pole of said source of electrical energy; an electrically operated signal device interposed 115 120 125 130

- in circuit with said permanent ground; means at each substation for operating the electrical contact making means and the ground contact whereby a metallic circuit will be completed through any one or more of the metallic conductors and at the same time completing a circuit through the signal device interposed in circuit with said permanent ground.
8. A signal system comprising a source of electrical energy; a plurality of metallic conductors connected thereto extending from opposite poles of said source of electrical energy; an individual relay interposed in one member of each pair of metallic conductors; local circuits controlled by each of said relays, each circuit including a key jack normally closing the circuit and a relay controlling a second local circuit, said second local circuit including a common register; a third local circuit in parallel with the first mentioned local circuit including visible signals and a relay; and a fourth local circuit controlled by said last mentioned relay, said fourth local circuit including an audible signal; electrical contact making means in circuit with said pairs, one at each substation; a ground circuit at each substation including a ground contact normally out of electrical connection with said conductors; a permanent ground connected to one pole of said source of electrical energy; an electrically operated signal device interposed in circuit with said permanent ground; means at each substation for operating the electrical contact making means and the ground contact whereby a metallic circuit will be completed through any one or more of the metallic conductors and at the same time completing a circuit through the signal device interposed in circuit with said permanent ground.
9. A signal system comprising a source of electrical energy; a plurality of metallic conductors connected thereto extending from opposite poles of said source of electrical energy to substations to form pairs; an individual relay interposed in one member of each pair of metallic conductors; local circuits controlled by each of said relays, each circuit including a key jack normally closing the circuit and a relay controlling a second local circuit, said second local circuit including a common register; a third local circuit in parallel with the first mentioned local circuit including visible signals; electrical contact making means in circuit with said pairs, one at each substation; a ground circuit at each substation including a ground contact normally out of electrical connection with said conductors; a permanent ground connected to one pole of said source of electrical energy; an electrically operated signal device interposed in circuit with said permanent ground; means at each substation for operating the electrical contact making means and the ground contact whereby a metallic circuit will be completed through any one or more of the metallic conductors and at the same time completing a circuit through the signal device interposed in circuit with said permanent ground.
10. A signal system comprising a source of electrical energy; a plurality of metallic conductors connected thereto extending from opposite poles of said source of electrical energy to substations to form pairs; an individual relay interposed in one member of each pair of metallic conductors; local circuits controlled by each of said relays, each circuit including a key jack normally closing the circuit and a relay controlling a second local circuit, said second local circuit including a common register; a third local circuit in parallel with the first mentioned local circuit including visible signals and a relay; and a fourth local circuit controlled by said last mentioned relay, said fourth local circuit including an audible signal; electrical contact making means in circuit with said pairs, one at each substation; a ground circuit at each substation including a ground contact normally out of electrical connection with said conductors; a permanent ground connected to one pole of said source of electrical energy; an electrically operated signal device interposed with said permanent ground; means at each substation for operating the electrical contact making means and said ground contact whereby a metallic circuit will be completed through any one or more of the metallic conductors and at the same time completing a circuit through the signal device interposed in circuit with said permanent ground.
11. A signal system comprising a source of electrical energy; a plurality of metallic conductors connected thereto extending from opposite poles of said source of electrical energy to substations to form pairs; an individual relay interposed in one member of each pair of metallic conductors; local circuits controlled by each of said relays, each circuit including a key jack normally closing the circuit; a common signal device controlled by said last mentioned relays; electrical contact making means in circuit with said pairs, one at each substation; a ground circuit at each substation including a ground contact normally out of electrical connection with said conductors; a permanent ground connected to one pole of said source of electrical energy; an electrically operated signal device interposed in circuit with said permanent ground; means at each substation for operating the electrical contact making means and said ground contact whereby a metallic circuit will be completed through any one or more of the metallic conductors and at the same time completing a circuit through the signal device interposed in circuit with said permanent ground; an individualizing circuit including a plug adapted to be inserted in

said key jack, thereby disconnecting the common register, and an individual signal receiving device.

12. A signal system comprising a source 5 of electrical energy; a plurality of metallic conductors connected thereto extending from opposite poles of said source of electrical energy to substations to form pairs; an individual relay interposed in one member 10 of each pair of metallic conductors; local circuits controlled by each of said relays, each circuit including a key jack normally closing the circuit; a common signal device controlled by said last mentioned relays; 15 electrical contact making means in circuit with said pairs, one at each substation; a ground circuit at each substation including a ground contact normally out of electrical connection with said conductors; a permanent 20 ground connected to one pole of said source of electrical energy; an electrically operated signal device interposed in circuit with said permanent ground; means at each substation for operating the electrical contact 25 making means and said ground contact whereby a metallic circuit will be completed through any one or more of the metallic conductors and at the same time completing a circuit through the signal device interposed in 30 circuit with said permanent ground; an individualizing circuit including a plug adapted to be inserted in said key jack thereby disconnecting the common register, an individual signal receiving device, a two- 35 way key, an individual register, and an audible signal device.

13. A signal system comprising a source of electrical energy; a plurality of metallic conductors connected thereto extending 40 from opposite poles of said source of electrical energy to substations to form pairs; an individual electrically operated signal device interposed in one member of each pair of metallic conductors; a differential wound 45 relay interposed in each pair of metallic conductors; a local circuit controlled by said differential relay including visible signals; electrical contact making means in circuit with said pairs, one at each substation; a ground circuit at each substation including 50 a ground contact normally out of electrical connection with said conductors; a permanent ground connected at one pole of said source of electrical energy; an electrically 55 operated signal device interposed in circuit with said permanent ground; means at each substation for operating the electrical contact making means and said ground contact whereby a metallic circuit will be completed 60 through any one or more of the metallic conductors and at the same time completing a circuit through the signal device interposed in circuit with said permanent ground.

14. A signal system comprising a source 65 of electrical energy; a plurality of metallic conductors connected thereto extending from opposite poles of said source of electrical energy to substations to form pairs; an individual electrically operated signal 70 device interposed in one member of each pair of metallic conductors; a differentially wound relay interposed in each pair of metallic conductors; a local circuit controlled by said differential relay including visible 75 signals; a relay; a second local circuit controlled by said last mentioned relay, including a visible signal; electrical contact making means in circuit with said pairs, one at each substation; a ground circuit at each 80 substation including a ground contact normally out of electrical connection with said conductors; a permanent ground connected to one pole of said source of electrical energy; an electrically operated signal device 85 interposed in circuit with said permanent ground; means at each substation for operating the electrical contact making means and said ground contact whereby a metallic circuit will be completed through 90 any one or more of the metallic conductors and at the same time completing a circuit through the signal device interposed in circuit with said permanent ground.

15. A signal system comprising a source 95 of electrical energy; a plurality of metallic conductors connected thereto extending from opposite poles of said source of electrical energy to substations to form pairs; an individual electrically operated signal device 100 interposed in one member of each pair of metallic conductors; a differentially wound relay interposed in each pair of metallic conductors; a local circuit controlled by said differential wound relay including visible 105 signals, a relay; a second local circuit controlled by said last mentioned relay including a visible signal; a second relay; a third local circuit controlled by said second relay, including an audible alarm; electrical 110 contact making means in circuit with said pairs one at each substation; a ground circuit at each substation including a ground contact normally out of electrical connection with said conductors; a permanent 115 ground connected to one pole of said source of electrical energy; an electrically operated signal device interposed in circuit with said permanent ground; means at each substation for operating the electrical contact 120 making means and said ground contact whereby a metallic circuit will be completed through any one or more of the metallic conductors and at the same time completing a circuit through the signal device interposed 125 in circuit with said permanent ground.

16. A signal system comprising a source of electrical energy; a plurality of metallic

- conductors connected thereto extending from opposite poles of said source of electrical energy to substations to form pairs; electrical contact making means in circuit with said pairs, one at each substation; a ground circuit at each substation including a ground contact normally out of electrical connection with said conductors; a permanent ground connected to one pole of said 5 10 15 20 25 30 35 40 45 50 55 60 65 70 75 80 85 90 95 100 105 110 115 120 125 130 source of electrical energy; a relay interposed in circuit with said ground; a local circuit controlled by said relay including a two-way two-pole key, a common register and a common audible signal device whereby either the common register or common audible signal device may be connected in circuit; means at each substation for operating the electrical contact making means and said ground contact whereby a metallic circuit will be completed through any one or more of the metallic conductors and at the same time completing a circuit through the signal device interposed in circuit with said permanent ground.
17. A signal system comprising a source of electrical energy; a plurality of metallic conductors connected thereto extending from opposite poles of said source of electrical energy to substations to form pairs; an individual electrically operated signal device interposed in one member of each pair of metallic conductors; a differentially wound relay interposed in each pair of metallic conductors; a local circuit controlled by said differential relay including visible signals and a relay; a second local circuit controlled by said last mentioned relay including a visible signal; electrical contact making means in circuit with said pairs one at each substation; a ground circuit at each substation including a ground contact normally out of electrical connection with said conductors; a permanent ground connected at one pole of said source of electrical energy; an electrically operated signal device interposed in circuit with said permanent ground; means at each substation for operating the electrical contact making means and said ground contact whereby a metallic circuit will be completed through any one or more of the metallic conductors and at the same time completing a circuit through the signal device interposed in circuit with said permanent ground; a local circuit including a contact making device and a third winding on said differential relay for restoring the armature of said relay.
18. A signal system comprising a source of electrical energy; a plurality of metallic conductors connected thereto extending from opposite poles of said source of electrical energy to substations to form pairs; electrical contact making means in circuit with said pairs one at each substation; a ground circuit at each substation including a ground contact normally out of electrical connection with said conductors; a permanent ground connected to one pole of said source of electrical energy; an electrically operated signal device interposed in circuit with said permanent ground; means at each substation for operating the electrical contact making means and said ground contact whereby a metallic circuit will be completed through any one or more of the metallic conductors and at the same time completing a circuit through the signal device interposed in circuit with said permanent ground; a jack key connected in circuit with each metallic pair; a hospital circuit including a plug adapted to be inserted in said jack key, a two-way two-pole key, a ground connected to said key and a signal recording device whereby the signal recording device may be operated through ground and either side of the line, or through the metallic line.
19. A signal system comprising a source of electrical energy; a plurality of metallic conductors connected thereto extending from opposite poles of said source of electrical energy to substations to form pairs; electrical signal devices connected in circuit with each pair of conductors; electrical contact making means in circuit with said pairs one at each substation; a ground circuit at each substation including a ground contact normally out of electrical connection with said conductors; a permanent ground connected at one pole of said source of electrical energy; an electrically operated signal device interposed in circuit with said permanent ground; means at each substation for operating the electrical contact making means and said ground contact whereby a metallic circuit will be completed through any one or more of the metallic conductors and at the same time completing a circuit through the signal device interposed in circuit with said permanent ground; a two-way two-pole key jack interposed in each pair of conductors normally connecting in circuit said first mentioned electrical signal devices; a telephone circuit connected to said two-way two-pole key jack whereby the telephone circuit may be bridged across a pair of conductors and the first named signal devices cut out of circuit; a circuit bridged across said pairs at the substation including a telephone bell, and a telephone jack adapted to receive the plug of a telephone set.
20. A signal system comprising a source of electrical energy; a plurality of metallic conductors connected thereto extending from opposite poles of said source of electrical energy to substations to form pairs; electrical signal devices connected in circuit with each pair of conductors; electrical contact making means in circuit with said pairs one at each substation; a ground circuit at each substation including a ground contact

normally out of electrical connection with said conductors; a permanent ground connected at one pole of said source of electrical energy; an electrically operated signal device interposed in circuit with said permanent ground; means at each substation for operating the electrical contact making means and said ground contact whereby a metallic circuit will be completed through any one or more of the metallic conductors and at the same time completing a circuit through the signal device interposed in circuit with said permanent ground; a two-way two-pole key jack interposed in each pair of conductors normally connecting in circuit said first mentioned electrical signal devices; a telephone circuit connected to said two-way two-pole key jack whereby said telephone circuit may be bridged across a pair

of conductors and the first mentioned signal devices cut out; a circuit bridged across said pairs at the substation including a telephone bell, and a telephone jack adapted to receive the plug of a telephone set; a two-pole key jack interposed in a pair of conductors and normally closing the conductor circuits; a telegraph circuit including a plug adapted to be inserted in said two-pole key jack, a sounder and a telegraph key; and a telegraph key bridged across said pairs at each substation.

In witness that I claim the foregoing I have hereunto subscribed my name this 29th day of December, 1910.

N. BANKS CREGIER.
